United States Patent Office

Des. 174,596
Patented Apr. 26, 1955

174,596

PLATE OR SIMILAR ARTICLE

John H. Reiser, South Gate, Calif., assignor to Wallace China Co., Ltd., Huntington Park, Calif., a corporation of California

Application November 15, 1954, Serial No. 33,100

Term of patent 14 years

(Cl. D44—15)

To all whom it may concern:

Be it known that I, John H. Reiser, a citizen of the United States, residing in South Gate, in the county of Los Angeles and State of California, have invented a new, original, and ornamental Design for a Plate or Similar Article, of which the following is a specification, reference being had to the accompanying drawing, forming part thereof.

The figure is a plan view of a plate or similar article, showing my new design.

The plate is of a conventional configuration when viewed from the side and bottom thereof.

I claim:

The ornamental design for a plate or similar article, substantially as shown and described.
